UNITED STATES PATENT OFFICE.

EMILIO IBARRA Y SURIS, OF HABANA, CUBA.

NON-REFILLABLE BOTTLE.

1,845,279.

Specification of Letters Patent. Patented June 29, 1920.

Application filed April 3, 1920. Serial No. 370,940.

To all whom it may concern:

Be it known that I, EMILIO IBARRA Y SURIS, a citizen of the Republic of Cuba, and resident of Habana, Cuba, have invented certain new and useful Improvements in Non-Refillable Bottles, of which the following is a specification.

The present invention relates to non-refillable bottles, and its object, briefly stated, is the provision of an improved article of the general character indicated which is so constructed as to preclude refilling of the bottle after its contents have once become exhausted. The invention also resides in the provision of a non-refillable bottle in which access to the controlling valve is entirely prevented, and which is comparatively simple and inexpensive in its construction.

According to the invention, the bottle essentially comprises a cylindrical body member or element and a spout member having approximately the shape of a goose-neck. These two members are provided at their contacting ends with inner and outer circumferential flanges. The outer flange on the spout member rests upon and is secured to the corresponding flange of the body member, while the inner flange of the spout member rests immediately upon the upper edge of the body member and has a portion which overhangs and is spaced from the inner flange on the body member. In addition to the two parts thus stated, the bottle comprises a third member in the form of a double or two-part valve casing, the lower member of which is formed with an out-turned circumferential flange which fits in the space between the two inner flanges, above mentioned, and is held in place thereby. The two parts of this double casing are of frusto-conical shape and are arranged with their small ends in connection, and the upper part receives the ball valve which is prevented from becoming displaced by means of an apertured top with which that part is provided. Owing to the goose-neck formation of the spout member, the outer branch thereof will be disposed to one side of the inner branch which incloses the valve casing, so that access to the valve for the purpose of removing it from its seat and thereby permitting refilling will be prevented.

An embodiment of the invention is illus-

trated in the accompanying drawing, in 55 which:—

Figure 1 is a longitudinal vertical section of the improved bottle; and

Fig. 2 is a plan view of the valve casing.

As shown in said drawing, and as previously stated, the bottle comprises two main parts or members, viz., the cylindrical body member 1 and the pouring member or spout 2, the latter having substantially the shape of an inverted goose-neck. The body member 1 is provided at its upper portion with an inner circumferential flange 4 and with an outer circumferential flange 3, both of which are located close to but are spaced from the upper edge of that member. 70

The upper member 2 comprises inner and outer branches 5 and 7, the former of which has a lower diameter substantially equal to that of the body member 1, while the outer branch 7 is disposed at one side of the axis of the inner branch and, hence, of the body member and has a greatly reduced diameter with respect to said inner branch. The outer end of this branch 7 is designed to receive a plug, cork or other closure 8. The inner branch 5 is formed at its free lower edge with an out-turned circumferential flange 6 and with an inner or in-turned circumferential flange 11. The latter flange being disposed a slight distance above the former. The outer flange 6 has the same width as the corresponding flange 3 on the body member 1 and rests immediately upon that flange and is suitably secured thereto as by welding, cementing or in some other 90 analogous way. The inner flange 11 rests upon the upper edge of the body member, as clearly shown in Fig. 1, and projects over and in spaced relation to the inner flange 4 on the body member, so that there is thus 95 defined an annular space or recess between the two flanges 4 and 11.

The bottle also comprises a valve casing indicated generally at 9 and consisting of upper and lower frusto-conical parts which 100 are arranged with their small ends in connection. The upper part 14 of the casing contains the ball valve 16 which latter normally occupies a substantially hemi-spherical seat 15 provided at the junction of the 105 two parts of the casing so as to control the passage of the liquid from the body member of the bottle to the spout. The ball is

designed to have play within the aforesaid upper part 14 to permit the passage of the liquid into the spout, but is prevented from falling out of part 14 by means of the cover 5 or top 18 with which the latter is provided, such cover having outlet openings 17 for the liquid, as indicated in Fig. 2.

The lower part of the valve casing, which is of greater diameter than the upper part, 10 is provided at its lower end with an out-turned circumferential flange 10 which fits in the space between the two inner flanges 11 and 4, suitable packing rings 12 and 13 being interposed between the opposite faces 15 of the flange 10 and the adjacent faces of the flanges 11 and 4, so as to enable the necessary tight joints to be obtained. In this way, the valve casing is securely locked in place, and as it is entirely inclosed by the 20 relatively large inner branch 5 of the goose-neck spout, access to the valve for the purpose of removing it from its seat and thereafter refilling the bottle will be rendered impossible, due to the curvature of the outer branch or arm of the goose-neck.

It is to be understood that in assembling the parts, the valve casing and its valve are positioned upon the inner flange 4 of the body member before the spout member is 30 put in place, the subsequent positioning of the spout member having the effect of locking the casing in place as has already been

explained. The bottle, as a whole, may be constructed of any suitable material and may be made in different sizes to contain 35 different amounts of liquid.

I claim as my invention:

In a non-refillable bottle, the combination of a body member having its upper portion formed with inner and outer circumferential flanges both of which are spaced from the upper edge thereof; a spout member curved laterally to one side of the axis of the body member and formed at its lower edge with inner and outer circumferential 40 flanges which rest, respectively, on the upper edge of the body member and on the first-named outer flange, the second-named inner flange having a portion thereof overlapping and spaced from the first-named inner 45 flange; a valve casing arranged within the spout member and having the form of superposed upper and lower frusto-conical parts provided at their junction with a valve seat; and a ball valve disposed within 50 the upper part of said casing and normally occupying said seat, said upper casing part having a perforated top to permit the passage of liquid therethrough while preventing the displacement of the ball valve therefrom.

Signed at Habana, Cuba, this 26th day of March, A. D. 1920.

EMILIO IBARRA Y SURIS.
